(57) **CLAIM**

The ornamental design for a bottle warmer, as shown and described.

DESCRIPTION

FIG. 1 is a top perspective view of a bottle warmer, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged plan view of the top surface;

FIG. 8 is an enlarged plan view of the bottom surface; and,
FIG. 9 is a top perspective view showing the bottle warmer in a disassembled state.

The broken lines in the drawings illustrate the portions of the bottle warmer, which form no part of the claimed design.
